CALENDAR

Albert G. Maddock, Detroit, Mich.

Application October 16, 1935, Serial No. 45,206

10 Claims. (Cl. 40—109)

This invention relates to a calendar. It has to do especially with a calendar of an adjustable nature and which may be used by direct adjustment for a number of years, and which, by reference to a table, may be used to ascertain dates over an indefinite number of years.

There are a number of objects to the invention. One of these objects is the provision of a calendar of the type mentioned which, it is believed, is reduced to its most simple form, so that it is easy to use, cheap to manufacture and readily understandable. Also, it is an object of the invention to produce a calendar which, although it may be made of pocket size and readily carried by one who needs such a calendar, is of such construction that the indicia thereon is not unduly small or hard to read, but to the contrary is relatively large and easily readable. To this end the calendar adapts itself for other kinds of uses; for example, it is readily adaptable for use as a desk calendar or a wall calendar, in which case it is feasible to make the printed matter of such size as to be easily readable from a distance, and yet the calendar may be made relatively small in over-all dimensions. A still further object of the invention is the provision of a calendar which provides on its face a relatively large area which may be used for advertising matter or other printed information. This is obtained even with a small pocket size calendar, while at the same time the printed matter used for calendar purposes may be of large type so that the same may be easily read, at a distance if necessary, and easily adjusted, thus minimizing the possibility of errors. These and other objects will become more apparent as the following detailed description is considered in connection with the accompanying drawings.

In these drawings:

Fig. 1 is a face view of a calendar constructed in accordance with the invention with parts cut away and parts shown in dotted lines.

Fig. 2 is a view of the back side thereof.

Fig. 3 is a view of the body of the particular calendar shown.

Fig. 4 is a back side view of the calendar showing the body portion enclosed upon an intermediate card member.

Fig. 5 is a somewhat enlarged view with parts cut away showing the intermediate card member.

Fig. 6 is an enlarged detail view of a portion of the card member illustrating the numbering arrangement.

Fig. 7 is a cross sectional view taken on line 1—1 of Fig. 5.

While the structure of the calendar, so far as the general invention is concerned, need not follow that shown herein, yet the structure shown is one suitable for pocket use, although the same structure may be used as a desk calendar and provided with means for causing the calendar to stand more or less erect, or a wall calendar, in which case it is preferably made larger. The body of the structure shown herein may be in the nature of an envelope 1 having a center part 2, 10 end flaps 3; a side flap 4 and a side flap 5. A card member 6 may be placed in the envelope and the same closed thereabout after the manner illustrated in Fig. 4. The body member has a slot 7 substantially at the fold line between the portions 2 and 5, and an opening 8 which lies mostly in the center part 2, but which projects slightly into the flap 4.

The card member shown in Fig. 6 has a width which is substantially equal to the width of the center portion 2 so that when the body is folded thereabout the edges of the card are accessible, as shown in Figs. 1 and 5, so that the card may be adjusted lengthwise in the envelope. For this purpose the card has a length less than that of 25 the center portion 2.

The portion 2 of the body is provided with seven apertures 10 positioned above the opening 8. The over-all length of the combined apertures is substantially the same as the length of the aperture 8, and the apertures are positioned one above another and in staggered relation, as shown. These apertures present a stair step formation.

Below the apertures 10 and above the opening 8, the face of the calendar, that is the center portion 2, is provided with indicia indicating the days of the week. In the present form this is shown as comprising the first letter of each day of the week (Fig. 1). This indicia extends across the top of the opening 8. Each letter may be 40 enclosed by lines, as shown. This entire day-of-the-week indicia is represented by the reference character 15.

Above the several apertures 10 there is a field blocked off into spaces for receiving the names of the months. As shown, this field, represented generally at 16, is divided into squares by printed lines. There are seven tiers or columns, each being in alignment with a day of the week and one of the openings 10. As shown, there are four 50 areas in a tier. However more areas in a tier may be used, and with the arrangement shown three areas in a tier may be used.

It will at once be appreciated that, although there are twelve months to the year, there are 55

only seven days of the week that the first of the month can fall upon. Except for leap year, January and October start on the same day of the week in any given year; February, March and 5 November start on the same day of the week; April and July start on the same day of the week. These months are grouped in tiers, as shown. May, June and August in any given year start on 10 days of the week different from any other month, and are therefore each separately located in a tier; September and December start on the same day of the week and are located in one tier.

To take care of leap year, January and February are shown twice in this field, one showing of 15 which is identified to stand out from the rest of the printed matter; for example, January is printed in heavy type in the column of April and July, since in a leap year the first day of each of these falls upon the same day of the week; February is printed in bold type in the column with 20 August, as these two months start on the same day of the week in a leap year. The indicia, in addition to showing the name of the month, may 25 also indicate the number of days in that particular month, as shown.

The card has printed matter or indicia thereon, as perhaps best shown in Fig. 5. The card bears numbers, generally shown at 17, for the 30 days of the month, arranged so that by shifting the card a month can be shown starting upon any day of the week. This is visible through the opening 8. For example, with the card positioned as shown in Fig. 5, the month starts on Saturday. In this position the card is located to the extreme right. As the card is shifted to the left the month varies and the limit of movement is when the digit 1 falls upon Sunday. This same arrangement is followed through for the second, third and fourth weeks in a month, and a portion 40 of the fifth week.

In addition, the card has year numbers thereon, generally identified as at 18. There are seven lines of year numbers positioned to line up with the seven apertures 10, and the lines are offset 45 or staggered as shown. Moreover, the year numbers in a line are in a proper sequence, determined to give the proper indication of a month. For instance, take the third line from the top, reading from right to left; it starts with 1934 50 and runs in sequence up to 1939, except for the insertion of 1941 between 1935 and 1936. This spaces 1935 and 1936 and is necessary because 1936 is a leap year. It happens that 1941 is the same as 1936 would be if it were not a leap year; 55 therefore, 1941 is used instead of 1936.

Another item is that of making the calendar useful as a reference calendar, or in the nature of a perpetual calendar so that reference can be made to years or months past or years or months 60 in the future to ascertain dates. To this end the calendar may have a table thereon as indicated in Fig. 2. The table is not shown complete, but sufficient portions thereof are indicated to clearly convey the thought; for instance, 1800 is 65 given the index number 1, 1804 is given the index number 4, 1996 is given the index number 5, etc. Now instead of complicating the structure by providing separate index numbers, the present arrangement contemplates using a digit in one of the year numbers shown in the indicia 18. The last digit of the year numbers may be used for this purpose. As shown in Fig. 6 the last digit 70 of each year is printed in bold type. Also 75 leap years may be printed in bold type.

The calendar is used as follows: Suppose one wishes to refer to the month of June, 1935; the card 6 is shifted right or left until the year number 1935 appears in the opening 10 which is in alignment with the month of June appearing in the field 16. The calendar is then in a position as shown in Fig. 5, and the month of June is indicated. The 31st day which is shown, may be disregarded, as the field indicates the number of days in the month of June. Suppose one wishes to have the calendar show the month of May, 1935; the card is shifted until the year number 1935 appears in the opening 10 under the month of May, (Fig. 1) then the calendar shows the month of May, 1935. This procedure may be carried out for any month falling in any of the years appearing in the indicia 18. On an ordinary year the January in the first column and February in the second column would be used. In leap years the January in the third column and the February in the sixth column, which appear in bold faced type, would be used.

Suppose now that one wishes to make reference to a back year, as for example 1849. The table as shown in Fig. 2 gives 1849 the index number 4. The index numbers in the table correspond to the last digit of the years in the indicia 18, namely, 4, 5, 6, 7, 8, 9 and 1; these digits appear in each line of the indicia 18. If the month of September or December is desired in 1849, the card is adjusted until the digit 4 appears through the opening 10 in alignment with the tier containing the months of September and December. This is the position shown in Fig. 5. The calendar now shows either September or December of 1849.

Again, for the year 1899, the table gives this year the index number 9. If the months of February, March or November are desired for this year the card is adjusted until the digit 9 appears, which is indicated in the position shown in Fig. 1. The same procedure is followed through for any year, and in any leap year the bold faced type showing January or February is used. It will be noted that the arrangement is such that in any adjustment of the card only one of the digits used for index numbers appears. In other words, in any given position of the card each index number appears once. This is illustrated in Fig. 1.

The fact that the calendar only shows one month makes it possible to have a small pocket sized calendar or a small desk calendar large enough to be readily visible and readable at a distance. Even in wall sizes the calendar does not have to be unduly large. Obviously in years to come the calendar may be varied by putting in different year numbers in the indicia 18. For example, in 1942, the calendar may show the years 1942 to 1947, inclusive, and 1949. Obviously this requires changing the index numbers on the reference table. In any group of seven consecutive years, two of such years are the same, apparently due to leap year; therefore it is preferred to skip one year in each group selected for use with this 65 calendar.

It is to be understood that the invention is not limited to the particular envelope and card structure shown, as I have shown the calendar in perhaps one of its most simple forms. More elaborate arrangements may be employed where such arrangements are desired. It will also be noted that while the reading matter may be quite large, due to the fact only one month is shown, 75

the reading matter as indicated herein takes up only one-third of the area on the face. Accordingly, the areas on each side of the reading matter, as indicated at 21, may be devoted to 5 advertisements or other printed information; or for that matter the reference table may be included on the face of the calendar.

In the claims appended hereto use is made of the terms "horizontal" and "vertical." Where 10 these terms are used, "horizontal" means the direction across the card or overlying member from right to left. "Vertical" means a direction from top to bottom as the device is viewed either in Fig. 1 or Fig. 5. Also, use is made of the term 15 "opening" with reference to the openings 8 and 10. What is meant here is that these are eight openings and need not necessarily be an aperture or a hole, but may be, in a more elaborate form of calendar, closed with a transparent piece 20 of material. Also it is said in the claims that the names of the months or days of the week are shown, and this is to be construed to include abbreviations thereof. Where in the appended 25 claims it is specified that certain of the digits are used for reference purposes, the meaning is that the calendar may be used to refer to years in the past or months in the past, or years or months in the future.

30 The side flap 5 may be perforated as at 25 and the flap 4 may be perforated as at 26. When folded around the card these perforated lines match and the lines define an intermediate tab. This tab may be bent outwardly, the tab being 35 shown at 27 in Fig. 7, so that the calendar may be made to stand up in an inclined manner. The flap 5 may be glued into position with the result that the two parts of the tab 27 are glued together. When bent out to the position shown in 40 Fig. 7 the material at the bend line of the flap 5 is placed under a compression greater than that of the material of flap 4, because it is on the inside of the bend, with the result that a strong 45 tab is provided which resists further bending, and in fact has a tendency to go back to its initial position. This serves admirably as a support, as the weight of the calendar tends to bend the tab further out from the body, which the tab effectively resists.

50 I claim:

1. A calendar comprising, a card member having indicia thereon for showing the days of the month and arranged to show months starting on 55 any one of the seven days in the week, said card having seven vertically spaced lines of year numbers and with each line staggered a distance of one year number relative to the next adjacent line, and a member overlying the card, said card 60 member and overlying member being adjustable relative to each other, said overlying member having a relatively large opening therein through which part of said indicia is visible to show a month, said overlying member having seven relatively 65 small openings each in horizontal alignment with a line of year numbers on the card, said openings being in stepped relation, and the total horizontal extent thereof being substantially equal to the horizontal width of the large opening, 70 said overlying member having a field thereon divided into seven vertical columns each in alignment with the name of one or more months of the year.

75 2. A calendar comprising, a card member hav-

ing indicia thereon for showing the days of the month and arranged to show months starting on any one of the seven days in the week, said card having seven vertically spaced lines of year numbers and with each line staggered a distance of 5 one year number relative to the next adjacent line, and a member overlying the card, said card member and overlying member being adjustable relative to each other, said overlying member having a relatively large opening therein through 10 which part of said indicia is visible to show a month, said overlying member having seven relatively small openings each in horizontal alignment with a line of year numbers on the card, said openings being in stepped relation, and the 15 total horizontal extent thereof being substantially equal to the horizontal width of the large opening, said overlying member having a field thereon divided into seven vertical columns, each in alignment with a relatively small opening, said columns 20 containing month names as follows: one column containing January and October; another February, March and November; another April and July; another May; another June; another August; and another September and December. 25

3. A calendar comprising, a card member having indicia thereon for showing the days of the month and arranged to show months starting on any one of the seven days in the week, said card having seven vertically spaced lines of year numbers and with each line staggered a distance of one year number relative to the next adjacent line, and a member overlying the card, said card member and overlying member being adjustable relative to each other, said overlying member having 30 a relatively large opening therein through which part of said indicia is visible to show a month, said overlying member having seven relatively small openings each in horizontal alignment with a line of year numbers on the card, said openings being in stepped relation, and the total horizontal extent thereof being substantially equal to the horizontal width of the large opening, said overlying member having a field thereon divided into seven vertical columns, each in alignment 35 with a relatively small opening, said columns containing month names as follows: one column containing January and October; another February, March and November; another April and July; another May; another June; another August; and another September and December; 40 said column containing April and July also containing the name January, and the column containing August also containing the name February, with said last named names January and February identified as different from the remaining month names for leap year purposes. 45

55 4. A calendar comprising, a card member having indicia thereon for showing the days of the month and arranged to show months starting on 60 any one of the seven days in the week, said card member having a plurality of lines of year numbers, with the lines in vertically spaced relation and in stepped relation, and a member overlying the card member, said card member and overlying member being relatively adjustable, said overlying member having a relatively large opening therein through which part of said indicia is visible to show a month, said overlying member having a plurality of relatively small openings each in horizontal alignment with one of the lines of year numbers and disposed in stepped relation, with the total horizontal extent thereof being substantially equal to the horizontal width of the large opening, said overlying member hav- 70 75

ing a field thereon divided into a plurality of vertical columns, each in alignment with a relatively small opening and each containing the name of one or more months of the year.

5. A calendar comprising, a card member having indicia thereon for showing the days of the month and arranged to show months starting on any one of the seven days in the week, said card member having a plurality of lines of year numbers, with the lines in vertically spaced relation and in stepped relation, the total width of all the lines substantially equal to the total width of the indicia, and a member overlying the card member, said card member and overlying member being relatively adjustable, said overlying member having a relatively large opening therein through which part of said indicia is visible to show a month, said overlying member having a plurality of relatively small openings each in horizontal alignment with one of the lines of year numbers and disposed in stepped relation, with the total horizontal extent thereof substantially equal to the horizontal width of the large opening, said overlying member having a field thereon divided into a plurality of vertical columns, each in alignment with a relatively small opening and each containing the name of one or more months of the year.

6. A calendar comprising, a card member having indicia thereon for showing the days of the month and arranged to show months starting on any one of the seven days in the week, said card having seven horizontal lines of year numbers with the lines vertically spaced and horizontally offset and having a total horizontal width substantially equal to the horizontal width of the said indicia, and a member overlying the card member, said card member and overlying member being relatively adjustable, said overlying member having an opening therein through which part of said indicia is visible to show a month, said overlying member having seven other openings therein each in horizontal alignment with one of the lines of year numbers on the card, said openings being in stepped relation corresponding to the horizontal offset of the lines of year numbers, said overlying member having a field thereon divided into seven vertical columns each in vertical alignment with one of the seven small openings and each containing the name of one or more months of the year.

7. A calendar comprising, a card member having indicia thereon for showing the days of the month and arranged to show months starting on any one of the seven days in the week, said card having seven horizontal lines of year numbers with the lines vertically spaced and horizontally offset and having a total horizontal width substantially equal to the horizontal width of the said indicia, and a member overlying the card member, said card member and overlying member being relatively adjustable, said overlying member having an opening therein through which part of said indicia is visible to show a month, said overlying member having seven other openings therein each in horizontal alignment with one of the lines of year numbers on the card, said openings being in stepped relation corresponding to the horizontal offset of the lines of year numbers, the total horizontal extent of said seven openings being substantially equal to the horizontal width of the first mentioned opening, said overlying member having a field thereon divided into seven vertical columns each in vertical alignment with one of the seven small open-

ings and each containing the name of one or more months of the year.

8. A calendar comprising, a card member having indicia thereon for showing the days of the month and arranged to show months starting on any one of the seven days in the week, said card having seven horizontal lines of year numbers with the lines vertically spaced and horizontally offset and having a total horizontal width substantially equal to the horizontal width of the said indicia, and a member overlying the card member, said card member and overlying member being relatively adjustable, said overlying member having an opening therein through which part of said indicia is visible to show a month, said overlying member having seven other openings therein each in horizontal alignment with one of the lines of year numbers on the card, said openings being in stepped relation corresponding to the horizontal offset of the lines of year numbers, said overlying member having indicia thereon extending horizontally adjacent the first mentioned opening showing the days of the week with the name of each day in alignment with one of the seven openings, said overlying member having a field thereon divided into seven vertical columns each in vertical alignment with one of the seven small openings and each containing the name of one or more months of the year.

9. A calendar comprising, a card member having indicia thereon for showing the days of the month and arranged to show months starting on any one of the seven days in a week, said card having seven lines of year numbers disposed in vertically spaced relation with the lines horizontally staggered, the last digit of each year number being arranged to be identified from the other numbers, and a member overlying the card member, said card member and overlying member being relatively adjustable, said overlying member having an opening through which part of the said indicia is visible to show a month, said overlying member having seven other apertures each in horizontal alignment with one of the lines of year numbers on the card, and said seven openings being stepped relative to each other so that the total width is substantially equal to the width of the first mentioned opening, said overlying member having a field thereon divided into seven vertical columns each in alignment with a relatively small opening and each containing the name of one or more months of the year, said last named digit of each year number, which is identified as specified, serving as an index number whereby the calendar may be used for reference purposes.

10. A calendar comprising a card member having indicia thereon for showing the days of the month and arranged to show months starting on any one of the seven days in a week, said card having seven lines of year numbers disposed in vertically spaced relation with the lines horizontally staggered, the last digit of each year number being arranged to be identified from the other numbers and a member overlying the card member, said card member and overlying member being relatively adjustable, said overlying member having an opening through which part of the said indicia is visible to show a month, said overlying member having seven other apertures each in horizontal alignment with one of the lines of year numbers on the card, and said seven openings being stepped relative to each other so that the total width is substantially equal to the width of the first mentioned opening, said overlying member having a field thereon divided into seven vertical columns each in alignment with a relatively small opening and each containing the name of one or more months of the year.

width of the first mentioned opening, said overlying member having a field thereon divided into seven vertical columns each in alignment with a relatively small opening and each containing the name of one or more months of the year, said last named digit of each year number, which is identified as specified, serving as an index number whereby the calendar may be used for ref-

erence purposes, and indicia on the overlying member representing the days of the week and positioned adjacent the first mentioned opening with the showing for each day being in vertical alignment with one of the columns and one of the said seven openings. 5

ALBERT G. MADDOCK.
